UNITED STATES PATENT OFFICE.

CHARLES F. KADE, OF PLYMOUTH, WISCONSIN, ASSIGNOR TO CHARLES F. KADE, JR.,
OF PLYMOUTH, WISCONSIN.

FOLDING TABLE.

1,217,772.

Specification of Letters Patent. Patented Feb. 27, 1917.

Application filed June 15, 1915. Serial No. 34,239.

To all whom it may concern:

Be it known that I, CHARLES F. KADE, a citizen of the United States, residing at Plymouth, in the county of Sheboygan and

State of Wisconsin, have invented new and useful Improvements in Folding Tables, of which the following is a specification.

The invention relates to tables, and more particularly to the class of folding tables.

10 The primary object of the invention is the provision of a table of this character wherein the construction thereof permits the automatic folding of the same with despatch, and when in folded position will occupy 15 the least possible space so as to allow the convenient storage or shipment of the table.

Another object of the invention is the provision of a table of this character wherein the same is adaptable for use as a card, 20 serving, dining, ice cream parlor, or drug store table, or for any other use, and will conveniently fold automatically, and with equal ease can be readily and quickly unfolded without possibility of pinching the 25 fingers of the user.

A further object of the invention is the provision of a table of this character which is simple in construction, neat and attractive in appearance, strong, durable, reliable 30 and efficient in operation, and inexpensive in manufacture.

With these and other objects in view, the invention consists in the construction, combination and arrangement of parts as will be 35 hereinafter fully described, illustrated in the accompanying drawing, and pointed out in the claim hereunto appended.

In the drawing:—

Figure 1 is a side elevation of a table constructed in accordance with the invention.

Fig. 2 is a vertical longitudinal sectional view.

Fig. 3 is a bottom plan view showing the table folded.

45 Similar reference characters indicate corresponding parts throughout the several views in the drawing.

Referring to the drawing in detail, the table comprises a top 5, preferably of circular shape, and made from wood, although the said top may be of any other desirable shape, and can be made from any other suitable material, having fixed to its under side a pair of spaced parallel cleats 6 to which 55 are swingingly connected a pair of support-

ing legs 7 united through the medium of a cross brace 8, the pivots 9 connecting the said legs 7 to the cleats 6 being passed through the legs and said cleats.

Swingingly connected to the legs 7 is another pair of legs 10, the pivots 11 connecting the said legs being passed through both pairs of legs at an intermediate point thereof. These legs 10 are joined to each other through the medium of a plurality of cross rungs 12, and to the under side of the top 5 intermediate the cleats 6 or centrally of the said top is a U-shaped resilient or spring guide strap 13 in which works the uppermost rung for guiding the legs 10 toward and away from a pair of spaced hook-like members 14 fixed to the under side of the said top 5 in the unfolding and folding of both pairs of legs 7 and 10, respectively.

Fixed to the rung next to the uppermost rung connecting the legs 10 is one end of a coiled retractile spring 15, which has its opposite end engaged in the under side of the top 5, and this spring serves to automatically move the legs 10 to unfolding position on the lifting of the said top 5, and during the movement of these legs 10 the legs 7 are also moved to unfolded position for supporting the top. This resilient guide strip 13 is slightly bowed upwardly or in the direction 85 of the under face of the top 5 so as to afford a clearance for the cross rung 12 to which the spring 15 is attached, and this strip 13 serves to act as a spring in throwing the legs 10 away from the top 5 for the opening of the 90 table.

On pushing inwardly upon the inner ends of the legs 10 against the resistance of the spring 15 both pairs of legs 7 and 10 will be 95 brought to folded position, and likewise the top folded substantially parallel therewith.

The table opens automatically, and to permit this it is only necessary to hold the top in a level position and drop the legs toward the floor, and in this movement the legs will 100 become unfolded automatically as the spring 15 acts to throw the legs 10 crosswise of the legs 7, and the uppermost cross rung 12 connecting the legs 10 will engage in the hook-like members 14 so that the table will be 105 firmly supported in position for use. Now to close the table it is only necessary to tilt the table backward with the left hand, letting the outer pair of legs rest firmly upon the floor, and by reaching underneath the top 110

with the right hand a hold can be had upon the uppermost rung, and on pulling upon it the table will fold.

From the foregoing description, taken in connection with the accompanying drawing, the construction of the device will be clearly understood, and therefore a more extended explanation has been omitted.

What is claimed is:—

- 10 A folding table comprising a top having spaced parallel cleats fixed to the under side of the same, a pair of leg frames pivoted to each other for swinging movement relative to one another, a pivot connecting one of the leg frames to the cleats, a U-shaped resilient guide fixed to the under side of the top be-
- 15

tween the cleats, a rung in the other leg frame and slidable through the guide, a second rung carried by the last named leg frame and adapted to contact with the guide 20 which serves as a spring for slightly pushing the leg frames away from the top when the leg frames and top are closed together, and resilient means connected to the second named rung and the top for automatically 25 spreading the legs on the raising of the top.

In testimony whereof I affix my signature in presence of two witnesses.

CHARLES F. KADE.
